UNITED STATES PATENT OFFICE.

MIKE NIKOLISH, OF WILLIAMSON, IOWA, ASSIGNOR TO AMERICAN MINING TOOL COMPANY, OF OTTUMWA, IOWA, A CORPORATION OF IOWA.

DRILL STRUCTURE.

Application filed April 9, 1928. Serial No. 268,569.

This invention relates to improvements in drill structures commonly known as mole foot heads of the type particularly designed for drilling blast holes in coal veins, and it has 5 for one of its objects to provide improved means for detachably securing the mole foot head or spiral auger conveyor on the square shank or shaft of the auger. Another object of the invention is to provide improved 10 means for holding the removable cutting bits securely in position in the mole foot head.

In prior devices it has been the practice to secure the mole foot head to the square shank of the auger by means of a spring cot- 15 ter, but this construction is objectionable because of the fact that the cotter pin being loose often works out of position and is lost. Also, bending it back and forth at the split soon breaks the cotter pin at this point and 20 it becomes ineffective to hold the mole foot head on the shaft. My improved securing means is in position at all times, is always out of the way when the head is in use, and securely keys the head to the square shank of 25 the auger at all times when in operative position.

In the drawings,—

Fig. 1 is a plan view of my improved mole foot head mounted in position upon the 30 square shank of an auger shaft, being partly broken away to show the means for holding the cutting bits in position;

Fig. 2 is a cross-sectional view on the line 2—2 of Fig. 1; and

Fig. 3 is a longitudinal sectional view 35 through my improved head taken on the line 3—3 of Fig. 2, and illustrating the locking key in elevation.

Referring to the drawings, 5 indicates the 40 mole foot head or spiral auger conveyor of the drill, which is usually provided with two spiral or helical conveying ribs 6, which, as the drill operates, conveys the material from the opening being drilled. The head 5 is cored out longitudinally as shown at 7 to receive the square shank 8 of an auger shaft. This cored out portion of the head tapers inwardly toward its inner end so that the tapered end of the square shank 8 fits snugly 45 therein, as shown in Fig. 3.

As shown in Fig. 1, a longitudinal slot 9 is provided in one of the helical conveying ribs 6 of sufficient width to receive a locking key 10. The locking key 10 extends longitudinally of the head and lies partly within

the slot 9, and is provided with a loop 11 at one end, said loop being pivotally mounted on a pivot pin 12 which passes through the helical conveying rib 6 at opposite sides of the slot 9.

The other end 13 of the locking key 10 is bent at an angle so as to pass through an opening 14 in the head and into an opening 15 in the square shank of the auger, which opening 15 is alined with the opening 14 when the 60 parts are in operative position, as shown in Fig. 3. On the opposite side from the opening 14 the head 5 is provided with an opening 16, alined with the openings 14 and 15, through which a suitable punch may be inserted for driving the bent end 13 of the locking key out of engagement with the opening 15 in the square shank 8 of the auger, if there is any tendency for the key to become bound against release.

It will be seen from the foregoing description that by the use of my improved locking key the head 5 may be quickly secured in place on the square shank 8 of the auger. Furthermore, this locking key cannot readily be 65 broken, and it cannot be lost as it is always held securely in place. Also, as it lies almost entirely in the slot 9 it is not in the way to prevent the material drilled out from readily passing along toward the rear of the head 70 between the helical conveying ribs as the device is being operated.

The head 5 is provided with a plurality of cutting bits 17, and another feature of my present invention is the improved means for 75 removably securing these cutting bits in position in the head. While I have shown my device as provided with two sets of these cutting bits, one on each side of the head, with three bits in each set, it is to be understood 80 that any number of bits may be used as desired. I shall only describe the mounting of one set of cutting bits, as the other set is similarly mounted in the head. I provide the outer end of the head with a plurality of 85 openings 18 for each set of bits, in the construction shown three such openings being provided, and these openings extend inwardly and communicate with a cored out portion 19 in the head (see Fig. 1). This cored out portion 105 tapers inwardly as shown, and the heels of the bits rest on the bottom of the cored out portion of the head so that the sides of the bits contact with each other at their lower ends, as shown. The wall of the head 110

adjacent the cored out portion 19 is provided with a screw-threaded opening 20 (see Fig. 1), in which threads a set screw 21. By tightening the set screw 21 the lower ends of the cutting bits 17 are wedged tightly together and against the opposite wall 19' of the cored out portion, and are thereby held securely in place, as will be readily understood. The cutting bits have a rather loose fit in the openings 18 so that the inner ends of the bits can move laterally into pressure engagement with each other under the action of the set screw 21. It will be readily apparent that by securing the bits as shown and described they will be prevented from accidentally falling out of the head, but they can be readily removed for sharpening or renewal when desired.

I claim:

- 20 1. A drill structure comprising in combination, an auger conveyor provided with a plurality of helical conveying ribs, a shaft on which said auger conveyor is mounted, and means pivotally mounted in one of said helical conveying ribs for detachably securing said auger conveyor on said shaft.
- 25 2. A drill structure comprising in combination, an auger conveyor provided with a plurality of helical conveying ribs, a shaft on which said auger conveyor is mounted, and means for detachably securing said auger conveyor on said shaft, said means comprising a latch pivotally mounted at one end in one of said helical conveying ribs, the other end of said latch being movable into and out of engagement with an opening in said shaft.
- 30 3. A drill structure comprising an auger conveyor provided with helical ribs, and means carried by one of said helical ribs for connecting said conveyor to a drill shank.
- 35 4. A drill structure comprising an auger conveyor provided with helical ribs, and means carried by one of said helical ribs for preventing longitudinal movement of said

auger conveyor with respect to a shaft on 45 which it is mounted.

5. A drill structure comprising an auger conveyor provided with helical ribs having a slot disposed between said ribs, a latch one end of which is pivoted to one of said ribs in 50 juxtaposition to said slot, the other end of which is formed to project through said slot and a hole in a shaft on which the structure is mounted to thereby hold the structure on the shaft.

55 6. A drill structure comprising an auger conveyor provided with helical ribs having a slot disposed between said ribs, an L-shaped latch one end of which is pivoted to one of said ribs in juxtaposition to said slot, the 60 other end of which is formed to project through said slot and a hole in a shaft on which the structure is mounted to thereby hold the structure on the shaft.

65 7. A drill structure comprising an auger conveyor provided with helical ribs having a slot disposed between said ribs and a second slot in one of the ribs, an L-shaped latch having a ring formed upon one end, said end being pivotally supported in said second slot, 70 the other end of which is projected through said first slot and a slot in a shaft registering therewith to hold the auger conveyor on said shaft.

75 8. A drill structure comprising an auger conveyor provided with helical ribs having a slot disposed between said ribs, an L-shaped latch one end of which is pivoted to one of said ribs in juxtaposition to said slot, the other end of which is formed to project so through said slot at one side of said auger conveyor and into a hole in a shaft on which the structure is mounted to thereby hold the structure on the shaft, said slot at the other side of said conveyor providing for the insertion of a tool for releasing said latch from position in said shaft.

MIKE NIKOLISH.
